UNITED STATES PATENT OFFICE

WALTER J. JOHNSON, OF CHICAGO, ILLINOIS, ASSIGNOR TO JOHNSON CHAIR COMPANY, OF CHICAGO, ILLINOIS, A CORPORATION OF ILLINOIS

ARMCHAIR

Application filed March 26, 1930. Serial No. 439,168.

This invention relates to arm chairs.

One of the objects of my invention is to provide an arm chair having a rigid back and having arms mounted solely on the back and wherein means is provided for pivotally mounting the arms and back relatively to the seat so as to permit the arms and back as a unit yieldingly to tilt backwardly relatively to the seat so that the occupant of the chair may, without lifting the feet from the floor, 10 lean backwardly into various positions, and in any of which the arms and back are supporting naturally and freely; and whereby also the arms of the chair assist in supporting 15 the body in correct posture.

Still another object of my invention is to provide an arm chair having a rigid back and having arms mounted solely on the back, wherein means is provided for pivotally 20 mounting the arms and back as a unit relatively to the seat so as to permit the arms and back yieldingly to tilt backwardly relative to the seat so that the occupant of the chair may lean backwardly in various positions, 25 and in any which positions the arms and back are supported naturally and freely, and wherein also the arms of the chair assist in supporting the body in correct posture.

Yet another object of my invention resides 30 in providing an arm chair constructed and arranged so that the occupant may sit in the chair with his feet firmly on the floor and may lean backwardly into various positions of torso posture, the arrangement of the 35 arms of the chair being such as to support the arms in a relaxed, natural position while the occupant is leaning rearwardly, and in such a manner that the arms are maintained in the same natural position relative to the 40 body.

Yet another object of my invention resides 45 in providing an arm chair having rigid arms and a rigid back pivotally tilttable rearwardly with respect to the seat of a chair and wherein means is provided for vertically ad- 50 justing the arms and back with respect to the seat so as to provide an adjustable arm support for persons of varying torso character- 55 istics.

These and other objects of my invention

will be apparent from a perusal of the following specification when taken in connection with the following drawings.

The accompanying drawings illustrate a selected embodiment of the invention and the 55 views therein are as follows:

Fig. 1 is a detail front perspective view of the improved chair.

Fig. 2 is a detail side perspective view thereof.

Fig. 3 is a detail side elevation of the improved chair showing an occupant seated 60 therein with the chair in tilted position.

Fig. 4 is a detail side elevation of the chair showing the manner in which the occupant 65 may shift his position.

In the accompanying drawings I have illustrated one type of my improved arm chair. In the illustration I have shown the chair as comprising a supporting base 5 including a 70 plurality of outwardly extending feet 7 supported on casters 6. The supporting legs 7 are adapted to support a seat 9, and to this end the base is provided with the usual threaded nut adapted to receive the screw 8 75 rigidly supported or carried by a casting secured to the underside of the seat 9. Means is provided for adjusting the vertical height of the seat 9 with respect to the supporting legs 7.

In the present case the arms and back as a unit, and the seat, are arranged to have relative tilting movement as the occupant leans 80 backwardly in the chair. In the present instance this relative tilting movement between 85 the back and arms as a unit and the seat is accomplished by having the seat arranged stationary with respect to the base 7 and the back and arms tilttable relatively to the seat, but obviously the invention is not so limited. 90 One of the distinguishing features of my invention resides in the fact that the seat and back do not tilt rearwardly as a rigid unit as in the case of a common present-day type of tilttable arm chair.

In the present instance I have shown the rigid back of the chair as comprising two outer vertical side members or rails 11 and 12, and upper and bottom cross rails 13 and 14 and back slats 15 connecting to the upper 100

and lower rails 13 and 14, respectively. The outer vertical rails 11 and 12 are rigidly connected to a cross support 16 to which a member having lugs 17 and 18, Fig. 2, is connected. A casting or connecting member 19 is pivoted to the main casting or seat support at 20 and to the lugs 17-18 at 21-22 respectively. The hand-nut 23 has operative engagement with a screw member 24 to effect tiltable adjustment of the back. A spring 25 having an adjusting wheel 26 is operatively connected to the pivotal member 19 to provide tension on the chair back to hold it normally in vertical position. When an occupant of the chair leans against the chair back the back is free to tilt yieldingly against the action of the spring 25.

The rigid back of the chair is provided with outwardly extending, rigid arms 28. These arms are rigidly connected preferably to the vertical members 11 and 12 of the back in any convenient manner such as by dowels. These rigid arms provide a rest for the elbows of the occupant of a chair as shown in Fig. 3 of the drawings and support the arms in natural and easy position. When the occupant of the chair rests his arm on the arm supports and leans backwardly into various posture positions, the arms of the chair not only support a portion of the weight of the occupant but also tend to maintain the body or torso of the occupant in correct sitting posture. These arms are supported by the braces or supports 29 which are preferably curved, as clearly shown in the various figures. The lower parts 30 of these braces or supports are rigidly fastened to the vertical members 11 and 12 and have their upwardly, outwardly, extending ends 31 engaging with and connecting to the bottom 32 of the arms 28.

Means is provided for adjusting the vertical height of the arms 28 with respect to the seat 9. For carrying out this purpose the cross-supports 16 of the chair back are adjustably connected to the member which has the lugs 17 and 18 thereon so as to permit the vertical adjustment of the back and arms relatively to the seat. This adjustment is maintained in any desired vertical position by means of a tightening member 27 as shown in Figs. 2 and 3.

It will be evident that as a result of the foregoing construction I have provided an improved type of arm chair wherein the arms and back tilt as a rigid unit relatively to the seat and from a point below the surface of the seat, preferably from a point below the rear-most portion of the seat. By means of this construction an occupant may sit in the chair with both feet firmly upon the floor or other support and may then lean backwardly into various desired positions and with his arms naturally and freely resting upon the arm supports. Due to the fact that the arms are supported solely from the shiftable back and

not from the seat, it will be evident that when the occupant tilts backwardly the arms supported on the arm supports 28 will likewise shift backwardly and will be maintained in substantially the same relative position with respect to the body whereby a free and easy restful posture is provided in leaning backwardly not only for the back itself, but also for the arms. When the occupant of the chair rests his arms on the arm supports and leans backwardly into various posture positions, the arms of the chair not only support a portion of the weight of the occupant but also tend to maintain the body or torso of the occupant in correct sitting posture.

Furthermore, by reason of the vertical adjustability of the arms with respect to the seat, these arms can be adjusted so as to provide correct arm adjustment support for persons having different torso structures thereby assuring a natural position of the arms when on the arm supports 28.

Another advantage of my improved type of arm construction resides in that in this chair the occupant may sit with his knees immediately under the central drawer support of a desk, i. e., close up to the desk and while in this position may tilt backwardly in the chair. This tilting movement is possible due to the fact that the seat or particularly the front portion of the seat does not rise to cause the legs to strike the under side of the desk drawer support as in the case of the common type of tiltable arm chair. In prior constructions of arm chairs this is not possible because the seat tilts rearwardly and the feet and knees are positioned under the central drawer support of a contour that will prevent the tilting of the seat, and hence the tilting of the arm chair.

It must be apparent that my invention is applicable to various types of designs of arm chairs and is not restricted to the type herein shown.

The invention is hereby claimed as follows:

1. An arm chair having supporting means, a seat, the arms and back comprising a rigid unit, means for mounting the seat on the supporting means, and a pivotal connection between the arms and back as a unit and the seat, the arms of the chair being wholly unsupported from the seat, said pivotal connection being located beneath the upper surface of the seat whereby the occupant may lean backwardly in the chair into various shifted positions of the torso and whereby in any such shifted position the occupant may distribute his weight partly upon the arms of the chair.

2. An arm chair having supporting means, a seat, the arms and back comprising a rigid unit, means for mounting the seat on the supporting means, and a pivotal connection between the arms and back as a unit and the

seat, the arms of the chair being wholly unsupported from the seat, said pivotal connection being located beneath the upper surface of the seat whereby the occupant may 5 lean backwardly in the chair into various shifted positions of the torso and whereby in any such shifted position the occupant may distribute his weight partly upon the arms of the chair, said arms being undercut to permit the leg of an occupant to project out through the side and under the overhanging arm whereby the occupant may 10 turn laterally in the chair.

3. An arm chair having supporting 15 means, a seat supported thereby, a rigid back having arms mounted solely thereon, and means for yieldingly and pivotally mounting the back and arms from a point below the upper surface of the seat to permit the back 20 and arms to tilt rearwardly relatively to the seat into various torso positions, and means for vertically adjusting the back and arms relatively to the seat to secure various easy arm-supporting adjustments for the arms of 25 the chair.

In witness whereof, I have hereunto subscribed my name.

WALTER J. JOHNSON.
